(57) **CLAIM**

The ornamental design for a venue entry unit, as shown and described.

DESCRIPTION

FIG. 1 is a front perspective view of the venue entry unit according to a first embodiment of the present invention.

FIG. 2 is a rear perspective view of the venue entry unit of FIG. 1.

FIG. 3 is a front view thereof.

FIG. 4 is a rear view thereof.

FIG. 5 is a left side view, the right side being a mirror image thereof, of the venue entry unit according to the first embodiment and also the second embodiment of the present invention.

FIG. 6 is a front perspective view of the venue entry unit according to the first embodiment with all displays in a stowed position.

FIG. 7 is a left side view with all displays in a stowed position, the right side being a mirror image thereof, of the venue entry unit according to the first embodiment and also the second embodiment of the present invention.

FIG. 8 is a front perspective view of the venue entry unit according to a second embodiment of the present invention.

FIG. 9 is a front view of the venue entry unit of FIG. 8.

FIG. 10 is a rear view thereof; and,

FIG. 11 is a front perspective view of the venue entry unit according to the second embodiment with all displays in a stowed position.

The broken lines depict portions of the venue entry unit that form no part of the claimed design.
